UNITED STATES PATENT OFFICE.

GEORGE F. BAHAN AND FREDERICK R. CHADWICK, OF CHARLOTTE, NORTH CAROLINA.

BOBBIN-STRIPPER.

1,121,602.

Specification of Letters Patent. Patented Dec. 22, 1914.

Application filed June 5, 1913. Serial No. 771,885.

To all whom it may concern:

Be it known that we, GEORGE F. BAHAN and FREDERICK R. CHADWICK, of Charlotte, in the county of Mecklenburg and State of North Carolina, have invented certain new and useful Improvements in Bobbin-Strippers; and we do hereby declare the following to be a full, clear, and exact description of the invention, such as will enable others skilled in the art to which it appertains to make and use the same.

The object of this invention is to provide improved means for automatically stripping waste yarn from bobbins.

15 A further object is to provide improved means for automatically feeding the bobbins to the strippers. And further objects of the invention are to insure the removal of any surplus waste that might be on the bobbins; and also to automatically remove 20 waste yarn from the device.

In the accompanying drawings Figure 1 is a side elevation. Fig. 2 is a plan view. Fig. 3 is an enlarged end view of the stripper, showing a portion of the feeder. Fig. 4 is a plan view of the stripper on an enlarged scale. Fig. 5 is an enlarged side view of the stripper.

Referring to the drawing, 1 designates a 30 main frame whereon is mounted an endless feeder 2, the particular construction of which may be widely varied, but preferably this feeder is composed of chain belts having connecting cross-pieces or slats 3 upon 35 which are mounted bobbin holders. Each of these holders is shown as comprising two socket pieces, one, 4, to receive the reduced end of a bobbin and the other, 5, the enlarged end thereof. These sockets 5 have 40 outwardly extending finger pieces 6. The bobbins are placed on an inclined table 7, and one by one are taken up by the sockets 4 and 5, the bobbins being directed into the sockets by finger pieces 6 which remove them 45 from fingers 8 at the lower end of the feed table. The upper flight of the feeder travels horizontally some distance, and as the belts make their turn downward the bobbins are 50 successively dropped into an inclined chute 9, being removed from the sockets by the bottom of the chute.

10 designates a bobbin-box which is designed to receive the bobbins from the chute and from which they will be ejected and in 55 the same movement be freed of the waste

yarn thereon. This box is shown as of rectangular formation, and between its opposite longitudinal sides is fitted a plunger head 12 which slides on guide rods 13. This head is provided with a socketed block 12^a, 60 preferably of rubber or other soft material, and designed to support the reduced end of the bobbin. The enlarged end of the latter is supported by a cross-plate 14 having a cut out to accommodate the bobbin-head, said 65 cross-plate being at the outer end of the bobbin-box and in about the same vertical plane as the sockets 5 of the feeder so that with the plunger-head in its retracted position the several bobbins after being discharged from the feeder will be properly supported within the bobbin-box.

The stripper is composed of a lower fixed, but preferably adjustably mounted, jaw 16, and an upper pivoted jaw 17, both jaws having 70 opposite semi-circular recesses, 75 conjointly forming an opening of sufficient diameter to insure engagement with the waste thread but without directly contacting with the bobbin itself. Adjacent to 80 these recesses the jaws are beveled to present reduced edges for effecting the stripping of the thread from the bobbins. The lower stripper-jaw 16 is vertically adjustable through a bolt 18 which may be turned when 85 the nut on a horizontally disposed bolt 19 is loosened, said latter bolt being projected through a vertically-disposed slot in the end of the bobbin-box.

The pivoted stripper jaw has its pivot at 90 20, and beyond its pivot has a weighted arm 21, the tendency of which is to normally hold said jaw opened, as shown in dotted lines, Fig. 3, to allow a bobbin to enter the bobbin-box. The side of the latter, at 22, 95 Fig. 3, which is slotted to accommodate the jaw, forms a stop to limit the movement of the jaw and thereby prevent direct engagement between the two jaws.

As soon as a bobbin is received in the bobbin-box the upper jaw 17 is automatically closed and held in its closed position while the bobbin is moved at right-angles to the two stripper jaws to remove the waste therefrom. For the purpose of insuring the removal of all waste, even when there is a surplus, we provide a knife 23 with which all surplus yarn will be caused to contact during the movement of the bobbin longitudinally of the bobbin-box. This knife is 100 105 110

shown as adjustably mounted on the jaw 17. (See Fig. 5.) Ordinarily the waste yarn will be removed by the stripper jaws, but when there is a surplus its removal is insured by the knife.

5 While the means shown for automatically holding the pivoted jaw closed may be widely varied, that shown comprises a double sector 24 mounted on a shaft 25 located 10 above and parallel with the bobbin-box. This sector is designed to engage an upwardly extending portion 26, of the jaw 17, but when either sector member moves out of engagement with the portion 26, the jaw 17 15 is immediately opened by the action of its weighted arm, and again closed when the other sector member engages therewith. We have shown the bearings of shaft 25 as extending upwardly from the bobbin-box 20 and as having a sprocket wheel 27 which is driven by a chain 28 from the main power shaft 29. The operating mechanism is clearly shown in Fig. 2, but it is unnecessary to describe it in detail other than to 25 state that it also drives a counter-shaft whereon is mounted a cam disk 30 to which is adjustably connected one end of a pitman 31, the other end of which is pivoted to the slotted end of plunger 12 for imparting to 30 the latter a reciprocatory motion in the bobbin-box. The power shaft 29 also carries the wheels by which the endless carrier is rotated, one of such wheels being shown at 32 in Figs. 1 and 3. This shaft also drives 35 a belt 33 for operating an exhaust fan 34 mounted on frame 1 beneath the bobbin-box, the purpose of such fan being to draw off and discharge the waste yarn.

In practice, the bobbins containing the 40 waste yarn are placed on the inclined table 7 and are successively taken up by the endless feeder and automatically discharged by the latter, one at a time, into the bobbin-box where the reduced end of each bobbin is 45 supported by the plunger block 12^a and the enlarged end by the recessed plate 14. Thereupon the upper jaw is closed by one of the sector members, and is held in its closed 50 position as the plunger moves in one direction, causing the bobbin to travel between the stripper jaws to effect the removal of the waste yarn. This movement also effects the discharge of the bobbin from the machine free of waste, and therefore it is unnecessary 55 to provide additional means to remove the bobbin from the bobbin-box. If any bobbin contains a surplus quantity of waste yarn the knife insures its removal. By the time a sector member disengages the pivoted jaw 60 the plunger has reached the limit of its outer travel and discharged the bobbin from the machine. The plunger thereupon starts on its return travel and has reached its starting point by the time the next bobbin 65 is dropped into the bobbin-box. As soon as

the jaw 17 is freed of the sector by which it was closed it automatically opens to allow the next succeeding bobbin to enter the bobbin-box.

The advantages of our present invention 70 will be readily appreciated by those skilled in the art. It will be seen that by means thereof all waste yarn may be readily removed from bobbins in a very short time and without danger of injuring the bobbin. 75 A machine so constructed is highly efficient and accurate in operation.

We claim as our invention:

1. In a bobbin stripper, in combination, 80 an endless feeder having supports for bobbins, a stationary bobbin-box into which the bobbins are designed to be discharged by gravity from the feeder, stripping means arranged transversely of the bobbin-box and comprising a pivoted jaw which is 85 opened to permit a bobbin to enter the bobbin box, means for automatically closing such jaw, and means for moving a bobbin transversely of the stripping means to strip the yarn from the bobbin as the latter is being ejected from the bobbin-box. 90

2. In a bobbin stripper, in combination, 95 an endless feeder having a series of bobbin supports, a stationary bobbin-box into which the bobbins are discharged by gravity, stripping means comprising a fixed jaw and a pivoted jaw, said jaws being mounted on the bobbin-box and arranged transversely thereof, means for normally holding the pivoted jaw open to allow a bobbin to enter the bobbin-box, means for automatically closing said jaw, and means for moving a bobbin relatively to the jaws as it is being discharged from the box. 100

3. In a bobbin stripper, in combination, 105 an endless feeder having a series of bobbin supports, a stationary bobbin-box into which the bobbins are discharged by gravity, stripping means comprising a fixed jaw and a pivoted jaw, said jaws being mounted on the bobbin-box and arranged transversely thereof, one of said jaws having a knife extending laterally from one of its sides, means for normally holding the pivoted jaw open to allow a bobbin to enter the bobbin-box, 110 means for automatically closing said jaw, and means for moving a bobbin relatively to the jaws and knife as it is being discharged from the box. 115

4. In a bobbin stripper, a stationary bobbin-box having a fixed rest for one end of a bobbin, a movable rest for the other end of the bobbin, stripping jaws mounted on said box adjacent to said fixed rest, one of said jaws being movable, means for opening and closing such latter jaw, and means for actuating said movable rest for ejecting a bobbin from the box, the stripper jaws stripping waste yarn from the bobbin when it is being so moved. 120 130

5. In a bobbin stripper, stripping means comprising a vertically disposed fixed jaw, a pivoted jaw movable in a vertical plane, a weight for normally holding said pivoted jaw open, means for feeding a bobbin between said jaws when opened, means for periodically engaging the pivoted jaw and holding it closed, and means for moving a bobbin relatively to said jaws.
- 10 6. In a bobbin stripper, a stationary bobbin-box having a bobbin rest, a vertically disposed fixed jaw arranged transversely of the bobbin-box, a pivoted jaw movable in a vertical plane for co-operating with the fixed jaw to strip waste yarn from a bobbin, said jaws having opposite recesses, a weighted arm for normally holding the pivoted jaw open, a constantly-revolving element for periodically engaging the pivoted jaw to close the same, and means for moving a bobbin relatively to the jaws as it is being ejected from said bobbin-box.
- 15 7. In a bobbin stripper, in combination, an endless feeder, a bobbin-box for receiving bobbins from the feeder, stripping means comprising a movable jaw, means for normally holding such jaw open to allow a bobbin to pass from the feeder into the bobbin-box, a constantly rotating shaft having a projecting member for periodically engaging the pivoted jaw to close the same, and means for ejecting a bobbin from the bobbin-box and moving it relatively to the stripping jaws while the pivoted jaw is closed.
- 20 8. In a bobbin stripper, in combination, an endless feeder, a bobbin-box for receiving bobbins from the feeder, stripping means comprising a fixed and a movable jaw, means for normally holding such movable jaw open to allow a bobbin to pass from the feeder into the bobbin-box, a constantly rotating double sector for periodically engaging the pivoted jaw and holding the same closed, and means for moving a bobbin relatively to the stripping jaws.
- 25 9. In a bobbin stripper, in combination, a constantly moving endless feeder having a series of bobbin-supports, a stationary bobbin-box, a chute between the bobbin-box and the feeder, said chute being arranged to automatically remove the bobbins from the feeder and direct them into said bobbin-box, and constantly operating means for stripping yarn from the bobbins as they are ejected from the bobbin-box.
- 30 10. In a bobbin stripper, in combination, an endless feeder having a series of bobbin-supports, a bobbin-box, a chute between the bobbin-box and the feeder, the bottom of said chute intersecting the path of travel of bobbins on said feeder for automatically removing the bobbins and directing them into said bobbin-box, and means for stripping yarn from the bobbins as they are ejected from the bobbin-box.
- 35 11. In a bobbin stripper, in combination, an endless feeder having a series of bobbin supports, fingers projecting from said bobbin supports, a rest for the bobbins from which they are removed by said fingers, a bobbin-box, bobbins being discharged by gravity from said feeder to the bobbin-box, and means for stripping yarn from the bobbins and ejecting them from the bobbin-box.
- 40 12. In a bobbin stripper, in combination, an endless feeder having a series of bobbin supports, fingers projecting from said bobbin supports, a rest for the bobbins from which they are removed by said fingers, a bobbin-box, a chute between the bobbin-box and the feeder, the bobbins being discharged over said chute to said bobbin-box, and means for stripping yarn from the bobbins and ejecting them from the bobbin-box.
